UNITED STATES PATENT OFFICE.

ROY H. McELROY, ALBERT G. LANGENKAMP, AND JOSEPH D. CITE, OF DAYTON, OHIO,
ASSIGNORS TO INTERNATIONAL CLAY MACHINERY COMPANY, OF DAYTON, OHIO, A
CORPORATION OF OHIO.

AUGER MACHINE.

Application filed July 6, 1925. Serial No. 41,799.

Our invention relates to auger machines.

It is the object of our invention to provide an auger machine which is susceptible of being divided into several parts for shipment but which, when assembled, has all the effect of a machine having a base made from a solid casting.

It is a further object of our invention to provide a combined auger machine and pug mill mounted upon such an integral base with a low center of gravity providing a rigid substructure.

It is an additional object of our invention to provide a unitary support for the driving pulley and its shaft for the interconnecting driving mechanism for the thrust bearing, the bearings for the pug mill shaft and the auger shaft.

It is a further object to provide a pug mill in which the pug mill blades are adjustable.

It is a further object to provide an auger singly or in this combination in which the auger blades are adjustable.

It is an additional object to provide means of preventing a stagnation of the material and a stoppage of it at the point of departure of the material from the pug mill to the auger.

It is a further object to provide means of access to the auger chamber by which the auger and liner may move without disturbing the remainder of the mechanism.

It is an additional object to provide in this combination a detachable liner.

It is an object to provide a combined pug mill and auger on a single shaft operated from a single source of power as a unitary mechanism.

Referring to the drawings:

Figure 1 is a plan view of the entire machine;

Figure 2 is a side elevation of the entire machine;

Figure 3 is an end elevation from the driving end;

Figure 4 is a section on the line 4-4 of Figure 1;

Figure 5 is an end elevation from the auger end of the machine;

Figure 6 is an inside end elevation of the auger casing;

Figure 7 is a detail view in section of the aperture for receiving lubricant which passes

from the spider to the bearing supporting the auger shaft;

Figure 8 is a detail plan view of the unit of the casting carrying the power driving mechanism;

Figure 9 is a section on the line 9-9 of Figure 8;

Figure 10 is a section on the line 10-10 of Figure 8;

Figure 11 is a side elevation in detail of this end of the casting partially in section on the line 11-11 of Figure 8;

Figure 12 is a section on the line 12-12 of Figure 8;

Figure 13 is an inside end elevation of the structure shown in Figure 8;

Figure 14 is an end elevation of the outside end of the casting partially in section on the line 14-14 of Figure 8;

Figure 15 is a plan view of the supporting auger casting;

Figure 16 is an enlarged detail end elevation of one of the adjustable pug mill knives;

Figure 17 is a side elevation thereof;

Figure 18 is a detail of the tapered key which holds the knife in position;

Figure 19 is an enlarged elevation of the spider and supporting bearing in the auger shaft;

Figure 20 is a section on the line 20-20 of Figure 19;

Figure 21 is a section on the line 21-21 of Figure 19;

Figure 22 is an enlarged section of the intermediate casting or base for the pug mill;

Figure 23 is an end elevation thereof; and

Figure 24 is a section through the auger casing and liners, face plate, extension, and hinged ring. The view also shows the extra large knives or impellers on the shaft adjacent the auger in the arrangement of the supporting spider and the auger with relation to the detachable liners, both primary and secondary;

Figure 25 is a section on the line 25-25 of Figure 26, of the extrusion end of the machine; and

Figure 26 is a detail elevation of the extrusion end of the machine.

Referring to the drawings in detail, it will be observed that the apparatus constituting our invention consists of three major

groups of mechanism each mounted upon its own integral base. The first group of mechanism is that which is concerned with the driving of the pug mill and the auger; the 5 second, is that embodying the pug mill, and the third is that embodying the auger. The three units can therefore be shipped separately and then assembled by means of locating dowel pins and bolts which pass through 10 two or more of the base castings to tie the entire structure together as a unit. This permits of economical shipping while at the same time securing the advantages of an integral base structure which must always be 15 assembled in the same way.

Referring to the power end of the device, it will be noted that the base upon which the mechanism is mounted consists of a single 20 integral casting having side walls 1 which are provided with flanges 2 and bolt receiving sleeves 3. On the outside end of the base casting having side walls 1 and a platform 4 is an upwardly projecting end casting 5 having a bearing receiving portion 6 for receiving the outer end of the shaft 7 of 25 the pulley 8. To this pulley is communicated power by any desired means. This shaft 7 rests at its other end upon a pair of bearing members 9 and 10 in the upwardly projecting casting block 11. These bearings supports 9 and 10 are separated to permit of 30 the location of the geared housing 12 in which are located conventional gears or a gear and chain of the usual type. This housing is provided with a handle 13 so that 35 it may be removed for inspection, adjustment and lubrication of the mechanism therein.

The mechanism in the housing 12 is connected to the main shaft 14 which is provided with a bearing support 15 on the base casting 16. It is also provided with a thrust bearing support 17. The actuating gearing lies between these bearing supports. 40 There is mounted on one end of the casting 16 a housing 18 for a ball bearing thrust for the main shaft 14. This main shaft becomes the pug mill shaft 19 when in the pug mill casing 20. This shaft is provided with a plurality of apertures 21 spaced from one another and located in rows along the axis of the shaft. Each row is substantially 45 90 degrees from the next adjacent row so that the pug mill blades 22 are at right angles to one another. These blades just clear the pug mill tub 20, the tub having a circular bottom and upwardly extending sides with an open mouth 23 to receive the material to be pugged. The side walls of the tub are held together intermediate their length by a transverse reinforcing bolt 24. The ends of the tub are mounted by bolts 25 in a U-shaped receiving end plate 26 which is bolted 50 on the first mentioned operating mechanism casting as at 27, thus serving to further

tie the unit together. The other end of the tub is mounted in a similar end casting 28 carried on the end of and as a part of the auger housing 29 which is mounted upon a base 30. On the right hand end of the pug mill is mounted the auger 31 in the housing 29. The bolts 32 and 33 which pass along either side of the pug mill tub and are connected in the operating mechanism casting and the auger casting tie the entire structure together. Within the base 34 of the pug mill are interiorly disposed bolts 35 and 36 which still further tie the several parts of the mechanism together. It will be noted in Figure 4 particularly in the section 55 that spacing sleeves 37 are provided on the bolts 33 and 32 the ends of which abut against the operating mechanism casting and the auger casting to properly space the several parts from one another. This base 60 casting 34 of the pug mill has a semi-circular top 38 for receiving the semi-circular bottom of the pug mill tub. The ends of the base 34 are provided with apertures 39 for the reception of bolts 35 and 36. The 65 interior of the base 34 is provided with spaced strengthening ribs 40.

The auger housing 29 is mounted on the base 30 and has an open inner end for receiving the auger 31 and an outer end closed 70 by the face plate 41 which carries the swinging gate 42 having the hinged arms 43 fitting with the hinged arms 44 of the plate on the hinged bolt 45. This gate is held by the bolt 46 in the jaws 47. In the gate is mounted the die 48. An extension 42a may be provided between the plate and the hinged gate. Through the die openings 49 is extruded the 75 plastic material worked upon by the pug mill and the auger. The auger shaft is supported, as will be seen in detail in Figure 19, in a bearing ring 50 which in turn is supported by a plurality of hollow arms 51 having shoes 52 on the outer end thereof fitting within the auger casing. These arms 80 and shoes are provided with lubricating apertures or pipes 53 which pass from the lubrication openings 76 shown in detail in Figure 7 and in Figure 19, to the bearing ring 50 so that lubricant can lubricate the 85 auger shaft. The arms are thin in the direction of movement of the material as will be seen in Figures 19 and 21, so that it is possible for the material to pass by the arms 90 with the minimum of resistance. As will be 95 seen in Figure 21, the arms are lozenge shape having sharp edges to facilitate the passage of material by the arms. Either end of the bearing 50 which is a cylindrical housing, is closed by a plate 55 to keep out foreign material and to keep in the lubricant. Grease 100 cups 56 feed lubricant from the outside of the auger housing 29 through the arms to the bearing. This form of spider support 105 for the auger end of the machine solves the 110 problem of lubricating the bearing. The 115 bearing 50 is supported by a bearing 120 housing 57 which is supported by a bearing 125 housing 58. The bearing 58 is supported by a bearing 130 housing 59. The bearing 59 is supported by a bearing 135 housing 60.

problem of adequately providing and supporting a lubricated bearing in the passage of the plastic material.

It will be noted that the bolts 35 and 36 pass through the base in this auger casting and are held in position by nuts on the outer end thereof. The other end of the bolts are located in the actuating mechanism casting base as illustrated.

10 The major tie bolts 32 and 33 are mounted in the eyes 57 of the auger casing which are located on either side of the casing on the outside. A strengthening rib 58 is located beneath and on the outside of the cylindrical casing which houses the auger. The auger casing is enlarged as at 59 to receive the bolt holes 60 which in turn receive the bolts that hold the face plate in position.

Turning to the bearing support for the auger from the spider arms, it will be noted in Figure 20 that the sleeve 50 carries at either end retaining rings 55 through the countersunk screws 62 mounted in the end of the sleeve 50. The inner faces of the 25 sleeve 50 are tapered at 63 to receive a V-shaped packing ring 64, the other side of which fits on the tapered surface 65 of a steel ring 66 turning with the shaft and mounted thereon by means of a key 67 loosely mounted in a key way 68 in a shaft, one end of which is open as at 69 adjacent the portion 70 of the shaft which is of lesser diameter than the portion 71, permitting of the moving of the spider and adjacent mechanism in 30 carrying the steel sleeve and key end of the shaft through one end of the auger casing. Between the inner wall of the bearing sleeve 50 and the steel sleeve 66 is a bronze bushing 72. This bushing has oil passages 73 cut away to communicate with the oil passageway 53. It will be noted that the alternate arms for the passageways 73 communicating therewith are directed in opposite directions in order to insure an equal distribution of the lubricant. This bronze bushing 45 72 is held in position by a set screw 74 carried by the bearing sleeve 50.

At the outer end of the arm 51 it will be observed that the casing of the auger marked 50 29 is provided an aperture 75 which has a V-shaped channel of greater diameter than the main aperture marked 76. In the end of the arm 51 is threaded a brass tubular member 77 adapted to communicate with the pipe 53. The upper end of this brass tubular member is enlarged as at 78 and carries a grease cup 56. After it has been inserted in the end of the arm Babbitt metal 80 is poured into the space 76 and flows into the 55 enlarged tapered portion 75, forming a shoulder. Thus a tight fit is made. The parts 77 and 78 are made of brass to prevent rusting.

60 Referring to Figure 8, for the marine bearing shown, designated 81, may have sub-

stituted in Figure 1, a plain ring bearing such as shown in connection with the other bearings in Figure 8 when the Timken roller bearing 18 is employed, but if the Timken roller bearing is not employed, then 70 the marine thrust bearing 81 is employed.

In operating the machine, we provide an operating handle 82 on a shaft 83 which passes beneath the auger casing where it is connected to a link 84 which is connected in 75 turn to the clutch 85 in any desired manner. This is not an essential portion of our invention, but we describe it in order to make a complete disclosure of an operating mechanism.

80 Turning to the auger casing once more with special reference to the detachable liners in the casing, it will be observed that the casing is provided with a shoulder 86 against which the feet 52 of the spider arms 85 abut. The other edges of the spider arms are engaged by the edges of the tapering liner members 87, which are in turn engaged on the other side by the secondary liner 88 which acts as a support for the primary liner 90 sections 89, 90 and 91. These liners are held in position by the face plate which is provided with a plurality of screws 92 which engage with the liners to hold them in position. The auger 31 is keyed on the shaft in 95 any desired fashion, and is detachably maintained on the shaft by the screw 93.

It will be noted that adjacent to the supporting bearing that the pug mill knives designated 94 have dual wings making them 100 approximately twice the size of the ordinary pug mill knife and they are located at a different angle to the main axis of the shaft, increasing the effect upon the material passing through the machine, thus insuring that 105 it shall be forced through the auger and insuring that the back pressure on the material will not cause it to eddy or slush at this point without movement which is a tendency 110 which has to be overcome by some such means as we have provided.

Having thus fully described our invention, what we claim as new and desire to secure by Letters Patent, is:—

115 1. In a combined pug mill and auger, a support, a pug mill tub, an auger casing, pug mill blades on a main shaft, a main shaft, an auger on said main shaft working in the auger casing and said pug mill blades adjacent the inner end of the auger set at a greater angle than the removing blades to increase the impetus common to the pug mill and in the auger at the point where the special blades are located.

120 125 2. In a combined pug mill and auger, a support, a pug mill tub, an auger casing, pug mill blades on a main shaft, a main shaft, an auger on said main shaft working in the auger casing and said pug mill blades adjacent the inner end of the auger set at an 130

angle to increase the impetus common to the pug mill and in the auger at the point where the blades are located, said blades being set at an angle different than that of the remainder of the pug mill blades.

3. In combination, a support, a shaft mounted on said support, actuating mechanism for actuating said shaft, a pug mill top in which said shaft rotates a portion of its

10 length, an auger casing in which said shaft rotates another portion of its length, pug mill blades mounted on said shaft in said tub, an auger mounted on said shaft in the auger casing, and special pug mill blades of

15 larger size and set at a more acute angle to the shaft than the other blades adjacent said auger for increasing the power applied to the material at the point where it enters the auger to force it through the auger and around the support for the auger shaft adjacent the auger, and a spider support for the auger shaft adjacent the auger.

4. In combination, a support, a shaft mounted on said support, actuating mechanism for actuating said shaft, a pug mill top in which said shaft rotates a portion of its 20 length, an auger casing in which said shaft rotates another portion of its length, pug

25 mill blades mounted on said shaft in said tub, an auger mounted on said shaft in the auger casing, special pug mill blades of larger size and set at a more acute angle to the shaft than the other blades adjacent said

auger for increasing the power applied to the material at the point where it enters the 35 auger to force it through the auger and by the support for the auger shaft adjacent the auger, and a spider support for the auger shaft adjacent the auger, said special blades being set at a different angle to the remainder of the blades on the shaft.

5. In combination, a support, a shaft mounted on said support, actuating mechanism for actuating said shaft, a pug mill top in which said shaft rotates a portion of its 40 length, an auger casing in which said shaft rotates another portion of its length, pug mill blades mounted on said shaft in said tub, an auger mounted on said shaft in the auger casing, special pug mill blades adjacent 45 said auger for increasing the power applied to the material at the point where it enters the auger to force it through the auger and by the support for the auger shaft adjacent the auger, and a spider support for 50 the auger shaft adjacent the auger, said special blades being set at a different angle to the remainder of the blades on the shaft, and of approximately double the area of the other blades.

In testimony whereof, we affix our signatures.

ROY H. McELROY.

ALBERT G. LANGENKAMP.

JOSEPH D. CITE.
